(57) CLAIM

The ornamental design for a multipurpose golf tool, as shown and described.

DESCRIPTION

FIG. 1 is a first top perspective view of a multipurpose golf tool, according to my new design;

FIG. 2 is a second top perspective view of the multipurpose golf tool;

FIG. 3 is a first bottom perspective view of the multipurpose golf tool;

FIG. 4 is a second bottom perspective view of the multipurpose golf tool;

FIG. 5 is a left side elevational view of the multipurpose golf tool;

FIG. 6 is a right side elevational view of the multipurpose golf tool;

FIG. 7 is a front side elevational view of the multipurpose golf tool;

FIG. 8 is a rear side elevational view of the multipurpose golf tool;

FIG. 9 is a top side view of the multipurpose golf tool;

FIG. 10 is a bottom side view of the multipurpose golf tool;

FIG. 11 is a perspective view of the multipurpose golf tool of FIG. 1 shown with the unclaimed removable ball marker removed for clarity of illustration;

FIG. 12 is a second perspective view of the multipurpose golf tool of FIG. 11; and,

FIG. 13 is a top side view of the multipurpose golf tool of FIG. 11.

The broken lines in the figures are included for the purpose of illustrating unclaimed portions of the multipurpose golf tool and form no part of the claimed design.

1 Claim, 11 Drawing Sheets
